AXEL W. PETERSON, OF SAN FRANCISCO, CALIFORNIA, ASSIGNOR TO CHARLES GROOS,
OF SAN FRANCISCO, CALIFORNIA.

WRENCH.

1,081,626.

Specification of Letters Patent. Patented Dec. 16, 1913.

Application filed March 19, 1912. Serial No. 684,783.

To all whom it may concern:

Be it known that I, AXEL W. PETERSON, a citizen of the United States, residing at San Francisco, in the county of San Francisco and State of California, have invented new and useful Improvements in Wrenches, of which the following is a specification.

The object of the present invention is to provide a nut or pipe wrench which can be quickly, easily and accurately adjusted into the proper position for operation, and, when adjusted, will not slip out of position.

In the accompanying drawings, Figure 1 is a broken side view of the wrench; Fig. 2 is a perspective view of a clamp plate used thereon; Fig. 3 is a similar view of a wedge used therein; Fig. 4 is a view similar to Fig. 1 of a modified form of the invention.

Referring to the drawing, 1 indicates the shank of the wrench, having thereon the fixed jaw 2 and the movable jaw 3, the latter formed with collars 4 surrounding the shank 1 and holding said movable jaw thereto. Said movable jaw is formed with an angular recess 8 to receive a clamp plate 9 and a wedge 14. Said clamp plate 9 is angular in form, having a portion 10 thereof extending parallel to the shank and formed with transverse corrugations 11 adapted to engage similar corrugations 12 in the adjoining face of the shank 1. It is also formed with a right-angled extension 13 through which is screwed a threaded portion 15 of a stem 22 extending through an aperture 7 in the inner wall 6 of said movable jaw 3, which forms the inner wall of said recess 8. Said stem has secured thereon a milled head 27 enabling it to be conveniently turned, said head being connected to said stem 22 by a conoidal portion 28 serving to space the head from the rear wall 6. A coiled spring 21 is interposed between the wall 6 and the angular portion 13 of the face plate. The forward end of the stem 15 is formed with a rounded knob 16 which is received within a transverse groove 17 formed in said wedge, said knob 16 having a contracted neck 18 engaging the reduced top 19 of said groove and preventing the knob being withdrawn therefrom. The oblique face of the wedge 14 engages an inner oblique face 5 of the jaw 3, which forms the oblique wall of the angular recess 8.

With a wrench constructed as above described the movable jaw 3 can readily be

pushed toward the stationary jaw, the effect of such movement being to compress the spring 21 if the clamp plate is still held back by reason of the engagement of the corrugations 11 with the corrugations 12, 60 said compressed spring acting, however, to advance the clamp plate and wedge as far as permitted by the angular front portion of the recess 8.

When pressure on the movable jaw toward the fixed jaw is removed, the spring acts to push the movable jaw back but very slightly, if at all, the maximum extent of such backward movement being the width of a corrugation 11, or 12, and the movable 70 jaw is securely held in this position, because any backward pressure on the movable jaw, being transmitted through the tapering wedge, has the effect only to press the corrugations 11 still more firmly into engagement 75 with the corrugations 12.

In order to withdraw the movable jaw from the fixed jaw, the head 27 is grasped with the fingers and withdrawn from the rear wall 6 or the fingers are pressed between said head and the rear face of the wall 6, and the wedge and clamp plate are withdrawn against the pressure of the spring 21 into a wider portion of the recess 8, the corrugations 11 slipping past the corrugations 12.

When the movable jaw is moved toward the fixed jaw, it is held against backward movement, as before described, only by the engagement of the corrugations 11 with the 90 corrugations 12, and it is therefore obvious that when moved into certain positions, it may be possible for it to move backward to the extent of nearly the width of a corrugation. In such case, if it be desired to cause 95 the movable jaw to fit tightly upon the article to be clamped, this may be effected by turning the head 27, which has the effect of advancing the wedge 14 and also the movable jaw 3 relatively to the clamp plate 9. 100

In the modification shown in Fig. 4, instead of making the wedge and clamp plate in two separate pieces, they are made in one piece, as shown at 30. A stem 31 is attached thereto, which passes through the aperture 7 in the wall 6, and the compressed coiled spring 21 is interposed between the rear end of the wedge 30 and said wall 6. A head 32 is loose on the outer end of the stem 31 projecting through said wall 6, and it is 110

formed with a crown cam or screw 33 which engages a stud 34 projecting laterally from said stem. It will be seen that by turning to the left the head 32 upon the stem 31, the wedge 30 will be withdrawn from the corrugations on the shank. On turning the head 32 to the right, the spring 21 will act to move the wedge 30 into engagement with the corrugations in the shank.

10 I claim:—

1. A wrench comprising a shank one side of which has transverse corrugations, a fixed jaw, a movable jaw having an angular recess, wedging means in said recess having 15 transverse corrugations for engaging the corrugations in the shank, a spring in said recess arranged to press said wedging means into the angle of the recess, a stem projecting rearwardly through said movable jaw, 20 and a head on said stem, said stem being provided with means whereby, when said head is turned, said movable jaw is moved

relatively to the corrugated part of said wedging means.

2. A wrench comprising a shank one side 25 of which has transverse corrugations, a fixed jaw, a movable jaw having an angular recess, wedging means in said recess having transverse corrugations for engaging the corrugations in the shank, a spring in said 30 recess arranged to press said wedging means into the angle of the recess, a stem projecting rearwardly through said movable jaw, the projecting portion of said stem being provided with means whereby said movable 35 jaw may be moved relatively to the corrugated part of said wedging means.

In testimony whereof I have hereunto set my hand in the presence of two subscribing witnesses.

AXEL W. PETERSON.
